UNITED STATES PATENT OFFICE

FREDERICK GEORGE WILDING, OF UNION CITY, NEW JERSEY

TYPE BURNISHER

Application filed May 5, 1927. Serial No. 188,999.

My invention relates to type burnishers and particularly to devices adapted to burnish type slugs after the same have been cast and has for an object to provide means for holding the slugs securely and in a position permitting a rubbing board carrying an abrasive material to be moved across the face thereof, thus removing all blisters and pits, leaving the surface of the type perfectly level.

5 A further object is to provide a device of this character of simple and inexpensive construction and adapted to be quickly attached or detached to a type slug casting machine.

10 Other objects and advantages reside in the special construction, combination, and arrangement of the various elements forming the invention as more fully hereinafter described and claimed, reference being had to the accompanying drawings forming part hereof, wherein like numerals refer to like parts throughout the specification, and in which:

15 Figure 1 is an end view of the slug holder and cleaner in operative position,

Figure 2 is a side view thereof,

Figure 3 is a detail perspective of the rubbing board and

20 Figure 4 is a fragmentary detail showing the abrasive material attaching means.

Referring now to the drawings, I have shown my invention comprising a burnishing slide 5 having a channel section formed longitudinally therein and within the base of which is cut a centrally disposed groove 6, the groove extending outwardly of the ends of the slide and adapted to receive the base section of a type similar to the Ludlow slugs, the slugs being adapted to have their upper faces extend slightly above the base of the channel section.

25 At each side of the channeled section I arrange steel runners 7 secured therein by screws or the like, said screws being countersunk therein.

30 I provide a rubbing board 8 of a size suitable to be slidably fit within the channeled section of the slide and extending slightly above the same so as to provide a gripping surface. On one face of the board I attach

a pair of runners 9, similar to the runners 7 arranged in the slide and adapted to slide thereupon. Between the runners I arrange a strip of abrasive material 10 preferably emery cloth or the like which extends over 55 each end of the board and is secured thereto by clamping members 11, said members having an inturned end provided with teeth for securely gripping the abrasive material.

The slide 5 is fixedly secured to a stand 60 12 provided with suitable openings 13 for attaching to a casting machine. Supporting blocks 14 are arranged to brace the slide upon the stand.

In the operation of the device it is obvious 65 that after the type slug has been placed in the groove 6 that the rubbing board with the abrasive material thereon face downwardly will come into contact with the upper surface of the type and by moving the slot 70 and the board thereover, it will operate to burnish the same.

It is obvious from the foregoing description that various changes and modifications may be made in the construction of the device without departing from the spirit of the invention or the scope of the appended claim and I accordingly claim all such forms of the invention to which I am entitled.

I claim:

35 In combination, a type slug holder adapted to be secured to a type casting machine or the like and having a channeled section provided therein with a groove extending downwardly therefrom, runners arranged 85 within the channeled section, a burnishing board slidably arranged within said channeled section and having runners disposed above the runners arranged therein, a strip of abrasive material secured to said board 90 between the runners and disposed above the groove in said holder in burnishing engagement with the lugs carried by the holder and abrasive attaching means carried at each end of the board releasably securing the opposite ends of the abrasive material in position thereon.

40 In testimony whereof I affix my signature.

FREDERICK GEORGE WILDING. 100
